[57] CLAIM

The ornamental design for a flexible hanger for foreign car mufflers, or similar articles, as shown and described.

DESCRIPTION

FIG. 1 is a left side elevational view of a flexible hanger for foreign car mufflers, or similar articles, showing my new design;

FIG. 2 is a front elevational view thereof, the rear elevational view thereof being a mirror image thereof;

FIG. 3 is a right side elevational view thereof; and
FIGS. 4 and 5 are respectively top and bottom plan views thereof.

FIG. 1

FIG. 2

FIG. 3

FIG. 4

FIG. 5
